(57) **CLAIM**

The ornamental design for a nozzle for vacuum cleaner, as shown and described.

DESCRIPTION

1. Nozzle for vacuum cleaner

1.1 is a front perspective view of a nozzle for vacuum cleaner;

1.2 is a rear perspective view thereof;

1.3 is a front view thereof;

1.4 is a rear view thereof;

1.5 is a left side view thereof;

1.6 is a right side view thereof;

1.7 is a top view thereof; and

1.8 is a bottom view thereof.

The broken lines indicate portions of the nozzle for vacuum cleaner that form no part of the claimed design.
